Louis Gaston Trinquart
INVENTOR:

by *Ott Munt*
his Attorney.

UNITED STATES PATENT OFFICE.

LOUIS GASTON TRINQUART, OF PARIS, FRANCE, ASSIGNOR TO THE BASSICK MANUFACTURING COMPANY, OF CHICAGO, ILLINOIS, A CORPORATION OF DELAWARE.

HIGH-PRESSURE LUBRICATING COMPRESSOR.

Application filed May 7, 1924, Serial No. 711,540, and in France January 18, 1924. Renewed January 26, 1928.

The lubricating compressors heretofore used where pressure is employed require the attention of both hands, one to hold the body of the compressor and the other to operate the piston and force it in far enough to discharge the lubricant from the compressor. The necessary use of both hands, however, form a serious impediment when lubricating the parts of a vehicle which are only accessible with difficulty.

It is with a view to eliminating this drawback that the applicant has devised the high pressure lubricating compressor which constitutes this invention and wherein the cylindrical part, which, in the compressors at present in vogue, plays the part of the compressor body or the pump cylinder, constitutes merely a reservoir for the lubricant and is conveniently associated with a small pump comprising a tube or cylinder, a piston or plunger and a valve. The parts are arranged in such a manner that the tube or cylinder and the plunger are maintained at a distance apart by a spring and the extremity of the tube or cylinder is kept in a position directly over the lubricant or dipping into it.

The compression and expulsion of the lubricant from the compressor is affected by a succession of reciprocating displacements of the tube relatively to the piston plunger whilst the compressor is held in one hand either by pushing on the compressor body or the extremity of the piston plunger according to circumstances.

A second characteristic feature of the invention consists in the combination with the lubricating device of a spherical junction or union-member located at the extremity of the tube, and making it possible to obtain a joint between the compressor and lubricator that remains tight during the lubricating operation even though the compressor be held in an inclined position.

The following description with the aid of the accompanying drawings shows by way of example several ways of carrying out the invention.

All the said drawings are in sectional elevation.

Figs. 1 and 2 represent one constructional form of the invention.

Figs. 3 and 4 represent an alternative form.

Fig. 5 gives a view of a detail and shows the spherical junction of the compressor when applied directly against the lubricator.

Figs. 6 and 7 show in longitudinal section two alternative forms of the invention.

In the constructional form shown in Figs. 1 and 2, the cylindrical part *a*, which, in the compressors at present in use operates as the compressor body and which will, for simplicity's sake be referred to under this designation, constitutes simply a lubricant reservoir and is closed by a base or end cap *a'* which is preferably not perfectly tight but adapted to allow of the ready access for the air to space *b*.

The forward extremity *a* of the compressor body may be fitted so as to slide upon a tube *c* which constitutes the pump cylinder, and a gland *d* may be provided to secure tightness. The tube *c* terminates in a nozzle *e*, preferably of spherical shape and adapted to make a tight fit with the circular opening of a lubricator inlet such as *f*, Fig. 5, even through the pump be held somewhat inclined relatively to the said inlet.

The piston plunger *g* which is attached to the bottom *a'* of the compressor body *a* is adapted to pass within the cylindrical part *c*. Between the bottom *a'* and the pump cylinder *c* is fitted a spring *h* which acts to keep the said piston plunger *g* and the cylinder apart, that is to say, to maintain the compressor in the position shown in Fig. 2.

Between the parts *c* and *c'* of the pump cylinder is inserted a valve, such as a ball valve *k* subject to the pressure of a spring *l*.

The lubricant is stored in the chamber *b'* and a partition wall *i* forms a tight joint between the two chambers *b* *b'*. This partition *i* may be arranged so as to slide longitudinally along a fixed tube *j* which is closed at its rear end by the bottom *a'* of the compressor whilst its forward end is provided with passages *j'*.

The manner of operating the improved lubricating compressor is as follows:—

The compressor body *a* is held by the hand and the nozzle *e* is applied to the lubricator as shown in Fig. 5. By a reciprocatory movement, the compressor body is then made to move to and from the lubricator, in other words, it is displaced from the position shown in Fig. 2 to that in Fig. 1 and con-

versely. Each displacement is accompanied by a corresponding pumping stroke of the piston *g* inside the cylinder *c'*, and, in consequence, by a very high pressure on the lubricant and the latter is expelled through the valve *k* and the nozzle *e*.

For example, supposing that a start be made from the position shown in Fig. 2 when the lubricant fills the chamber *b'* and the cylinder *c'* it will be seen that the plunger *g* as it passes into the said cylinder *c'* will exert pressure on the lubricant thereon to a high degree and thus drive it out by the valve *k* and the nozzle *e*, the parts of the compressor passing meanwhile to the position shown in Fig. 1.

If now, at this moment, the pressure be relaxed, though the nozzle *e* is still kept in contact with the lubricator *f*, the spring *h*, being under tension, will push back the compressor body and restore it to the position shown in Fig. 2. During this rearward movement the extremity of the plunger *g* has produced a vacuum in the cylinder *c'* as a result of the closing of the bottom of the cylinder *c'* by the ball valve *k* and in these circumstances whenever the piston uncovers the upper extremity of the cylinder *c'*, the lubricant contained in the chamber *b'* which is subjected to atmospheric pressure exerted on the partition *i* will flow in the direction of the arrows and recharge the cylinder *c'* referred to with the result that the compressor is restored to its initial condition.

It must not be forgotten that at each stroke of the pump the level of the lubricant is lowered and that the partition *i* is maintained in contact with the lubricant under the influence of atmospheric pressure and capillary forces. The flange *i'* of the partition *i* may be arranged at a higher level as shown in Figs. 3 and 4 so that the said partition will be, to a certain extent, floated upon the lubricant and will follow its movement exactly.

In order to avoid any compression of the lubricant within the tube *j* a suitable hole *p* may be provided.

In the constructional form illustrated in Figs. 3 and 4 the principle of operation is the same but it is the extremity *g'* of the piston rod or plunger *g* which is pushed by the hand to obtain the reciprocating movement, the spherical nozzle *e* remaining in contact with the lubricator and the cylindrical tube *c'* being fixed to body *a* of the compressor.

It may be remarked that the extremity *g'* of the piston plunger may act as a gland and be of lantern construction to ensure accurate guiding during its stroke, as shown in Fig. 4, while still permitting the lubricant contained in the chamber *b* to find its way into the pump cylinder *c'*.

It is self-evident that modifications may be introduced into the arrangement of the constituent parts of the compressor just described without departing from the principle of the invention, more particularly in cases where oil is employed instead of more solid lubricants, in which case the provision of a tube *j* or a partition *i* would serve no purpose, as the oil would, of itself, flow into the pump cylinder *c'* as soon as the extremity of the piston has cleared the cylinder.

In addition, the compressor described can operate when the nozzle *e* is not pressed against the lubricator but is suspended over the latter by some suitable device, or perhaps attached by a flexible tube to the body of the pump *c'*.

Further it is easy to imagine the cylinder to be situated not as shown and described in the foregoing examples, but to be transferred to the rear end *a'* of the compressor body, the piston plunger *g* being then of tubular construction to allow the lubricant to be compressed and expelled through the interior of the piston, see Fig. 7.

Whatever the construction form may be account has to be taken of the fact that, owing to the small diameter of the pump *c'* substantially high pressure may be obtained and that, on the other hand, the compressor body *a* constituting, as it does, merely a reservoir for the grease or lubricant, may have very thin walls and may for example, be constructed of tin plate.

In Fig. 5 the spherical nozzle end *e* is shown as pressed against the mouth *f* of the lubricator and it will be seen that the latter as well as the spring pressed valve *f'* are countersunk in such manner that they form together a recess or depression in which the nozzle *e* can steady itself, this depression is a help in centering the cap when it is difficult to make out the mouth of the lubricator.

I claim:

1. In a lubricating apparatus, the combination of a reservoir containing lubricant, means for separating successive fractions of said lubricant and distributing the same, and a movable partition engaging the body of lubricant and having a flange rigid with and substantially parallel to said partition and embedded in the body of lubricant.

2. In a lubricating apparatus, the combination of a lubricant reservoir, a pump comprising a piston and cylinder mounted in the reservoir and communicating therewith, a central tube arranged in the axis of the lubricant reservoir and rigid therewith, a movable partition embracing said tube and adapted to engage lubricant in said reservoir, and a coil spring for retracting said piston, said spring contained in said central tube.

3. In a lubricating apparatus, the combi-

nation of a lubricant reservoir, a high pressure pump comprising a piston and cylinder mounted in the reservoir and communicating therewith, a central tube arranged in the 5 axis of the lubricant reservoir and supported thereby, a movable partition embracing said tube and adapted to engage lubricant contained in said reservoir, said partition

comprising a disc-like part and a flange rigid with and substantially parallel to said part, and a coil spring contained in said central tube and serving to withdraw said piston from said cylinder.

In testimony whereof I affix my signature.

LOUIS GASTON TRINQUART.
